INSERTING TOOL FOR SNAP TIES

George Erbe, Jersey City, N. J.

Application January 27, 1951, Serial No. 208,200

1 Claim. (Cl. 24—201)

1

This invention relates to a tool for inserting tie rods on building wall forms.

It is an object of the present invention to provide a quick attachable and detachable tool adapted for connection to a tie rod whereby to locate the tie rod in hole in the opposite form from which it is connected in order that the forms can be pulled or pushed and spaced properly from one another and wherein the inserting tool can be readily released from the tie rod by a simple movement of the tool over the head on the tie rod.

Other objects of the present invention are to provide a tie rod inserting tool for forms used in wall constructions which tool is of simple construction, easy to attach to the tie rod, inexpensive to manufacture, has a minimum number of parts, strong, durable and efficient in operation.

For other objects and for a better understanding of the invention, reference may be had to the following detailed description taken in connection with the accompanying drawing, in which

Fig. 1 is a perspective view of the inserting tool for the tie rods embodying the features of the present invention.

Fig. 2 is a longitudinal sectional view taken on line 2—2 of Fig. 1.

Fig. 3 is a top plan view of the attaching portion of the tool.

Fig. 4 is a fragmentary sectional view of the portion of the tool which receives the tie rod with the enlargement of the tie rod disposed in the end of the tool and in place to effect the inserting operation thereof.

Fig. 5 is a longitudinal sectional view taken on line 5—5 of Fig. 1.

Referring now to the figures, 10 represents an attaching part of sleeve formation throughout a greater extent of the same and having a body portion 11. The portion 10 has a central opening 12 through which a cable cord 13 extends. The end of the cable cord is folded, as indicated at 14, whereby to hold the cable within the attaching part 10. The sleeve portion is integral with the body 11 and extends forwardly therefrom, as indicated at 15. In the sleeve portion is an elongated slot 16 which extends along one side of the portion and laterally, as indicated at 17, across an end formation 18 in the end of the sleeve. The slot 16 has transverse and inclined notches 19 and 20 adapted to receive a head 21 of a tie rod 22. This head 21 is fixed to the tie rod by a riveted connection. The head 21 will

2

pass downwardly through the laterally extending notches of the slot 16 and presented to the same in the manner as shown in Fig. 2 and upon drawing the rod forwardly, the head 21 will come to rest against the end formation 18. An upwardly struck stop portion 23 will hold the tie rod against rearward displacement in the attaching member 10.

The cable 13 has at its opposite end, a ball 24 adapted to pass into a sleeve or handle 25 with the cable 13 extending through slot 26. Stop projections 27 extend inwardly from the sleeve wall 25 so as to retain the ball against outward displacement from its center position. The handle 25 can be grasped to straighten the cable 13 and place an inserting force on the gripping or attaching piece 10 in order to insert the tie rod 22 into hole in opposite building form for proper engagement therewith. Thereafter the attaching piece 10 can be readily pivoted so that the head 21 can be released therefrom.

The sleeve or handle 25 as shown in Fig. 5 is not detachable from the cable 13 at any time, as this handle 25 is to be used as a handle which can be turned at a 90° angle, so as to enable a person to enter it in hole in form, from inside of the form due to its toggle bolt action. It will be further noted that notches 27 prevent the ball 24 from becoming disengaged at any time from said handle 25, but will further allow the handle 25 to be turned at 90° angle as also shown in Fig. 5, that is, from 13' to 13. It will be further seen that slot 26 enables the cable 13 to reach position 13' as shown in Fig. 5, thereby allowing handle 25 to pass through a hole which may be $\frac{5}{8}$ of an inch in a form assembly.

In the use of the attaching piece 10 the head is aligned with the downwardly and forwardly inclined lateral notches 19 and 20 in order to properly present the same to the opening 16, the tie rod 22 can be pulled through the slot 17 for engagement with the end formation 18. With the tie rod in place, an attaching piece 10 can be tilted to the side and pushed out of engagement with the head 21 allowing the head thereby to pass outwardly from the notches 19 and 20.

It should now be apparent that there has been provided a tool for use with tie rods that can serve to enter or insert the same in wall forms and which can be attached and detached from the tie rod in any easy manner.

While various changes may be made in the detail construction, it shall be understood that such changes shall be within the spirit and scope

of the present invention as defined by the appended claims.

Having thus set forth and disclosed the nature of my invention, what is claimed is:

A tie rod inserting tool adapted for connection with an enlarged head on a tie rod comprising a sleeve member having an elongated notch extending from the attaching end thereof laterally downwardly and forwardly extending notches for receiving the head on the tie rod whereby to permit the forward movement of the head through the attaching sleeve, said longitudinally extending slot being adapted to accommodate the tie rod and having a width only slightly larger than the diameter of the tie rod 15 and an end formation on the sleeve member having a slot to accommodate the tie rod, said end formation serving as an abutment for the enlarged head on the tie rod, and a transverse abutment lying forwardly of the laterally extending 20 notches of the elongated slot and disposed on the wall opposite the said elongated slot where-

by to prevent the rearward displacement of the enlarged head of the tie rod while the tie rod is axially aligned with the sleeve member.

GEORGE ERBE.
